UNITED STATES PATENT OFFICE.

EDWARD MORRIS, OF BOSTON, MASSACHUSETTS.

SIGNALING APPARATUS FOR STREET-RAILWAY CARS.

1,132,864.

Specification of Letters Patent. Patented Mar. 23, 1915.

Application filed March 16, 1914. Serial No. 825,055.

To all whom it may concern:

Be it known that I, EDWARD MORRIS, a citizen of the United States, residing at Boston, in the county of Suffolk and State of Massachusetts, have invented certain new and useful Improvements in Signaling Apparatus for Street-Railway Cars, of which the following is a specification, reference being had to the accompanying drawings.

10 This invention relates to an improved electrical signaling system for street railway cars, and has for its primary object to provide an electrically operated signal within view of the motorman, the circuit for which is closed only when all of the car doors are closed, thus obviating liability of accident which frequently occurs when the car is provided with the ordinary bell operated by the conductor.

20 The invention has for a further object to provide danger signal lamps arranged above each of the car doors, said lamps being connected in multiple through the medium of switches arranged in the door jambs with a common circuit, whereby when any one of the doors is in its open position, the lamp associated therewith will be illuminated.

The invention has for a further and more specific object to provide improved means 30 for connecting all of the signaling lamps upon a train of cars coupled together, in a common illuminating circuit.

As a still further object of the invention, I aim to provide a very simple and novel 35 switch construction arranged in the door jamb of the car whereby the purposes of the invention will be efficiently accomplished.

The invention has for a further general 40 object to provide a signaling apparatus of the above character which may be inexpensively installed in railway cars of the present construction without necessitating any material alterations therein and is reliable and positive in practical operation.

45 With the above and other objects in view as will become apparent as the description proceeds, the invention consists in certain constructions, combinations and arrangements of the parts that I shall hereinafter 50 fully describe and claim.

For a full understanding of the invention, reference is to be had to the following description and accompanying drawings, in which—

55 Figure 1 is a horizontal section through one car and a portion of another showing

the arrangement of the signal lamps and the circuit therefor; Fig. 2 is an enlarged vertical section through the switch box which is arranged in the door jamb. Fig. 60 3 is an enlarged longitudinal section of the electrical plug and socket connection between the opposed ends of the cars in a train; Fig. 4 is a detail section of the metal socket member removed from its insulating 65 casing. Fig. 5 is a transverse section taken on the line 5—5 of Fig. 4.

In Fig. 1 of the drawings, I have illustrated railways cars of that type generally employed upon elevated, subway and inter-urban lines, in connection with which the present invention is particularly designed for use, though it will be understood that with the adoption of very slight modifications, the signaling apparatus may also be 75 rendered applicable to various other types of cars. It will therefore be understood that the following specific reference to the car structure does not necessarily import any limitation into the invention as defined in 80 the subject matter of the appended claims.

Referring now in detail to the drawings and more particularly to Fig. 1 thereof, 5 designates the car body which is provided in opposite sides with a plurality of sliding 85 doors 6, for the entrance and exit of the passengers. At one side of the door opening, a switch box 7 is countersunk in the door jamb, said box being provided upon one end with an attaching plate 8 whereby the same 90 may be rigidly secured in place. The detail construction and arrangement of the parts of the switch mechanism will be later specifically set forth. 9 designates the motorman's compartments which are arranged 95 upon relatively opposite sides of the center of the car at the ends thereof. Suitable folding doors 10 are adapted to be arranged in position to divide off the motorman's compartments from the remainder of the car 100 occupied by the passengers when the motorman is stationed in said compartments. The door 10 at the opposite end of the compartment is adapted to be folded for a purpose which will be obvious. In each of the compartments 9, an electric signal lamp 11 (preferably white) is arranged, said lamp being disposed above and at one side of the controller 12. An electric lamp bulb 13 (preferably red) is also arranged above each 110 of the sliding doors 6. When the car is in operation, the motorman's signal lamp 11 is

illuminated while the other lamps 13 above the doors are extinguished, said latter lamps however, being illuminated when the passenger doors are open, as will be fully disclosed in the following description.

Attention is now directed to Fig. 2 of the drawings wherein I have shown the preferable construction of the automatic switch. A transverse bar or bracket plate 14 is rigidly fixed to one of the side walls of the switch box 7 and is provided with an opening to loosely receive one end of the movable plug or stem 15. The other end of this stem is provided with an enlarged cylindrical head 16 which is loosely movable through a central opening 17 provided in the attaching plate 8. A plug of insulating material indicated at 18 is fixed upon the stem 15 contiguous to the head 16 and within the box 7. A coil spring 19 bears at one of its ends against this plug and at its other end against the bracket plate 14, said spring normally acting to force the stem 15 outwardly. A ring or annulus 20 of metal or other suitable conductive material is carried by the insulating plug 18, and, when the switch plug is in its normal position, bears against the resilient contact plates 21 which are fixed at one of their ends within the box 7 and suitably insulated from the walls thereof. A second pair of opposed spring contact plates 22 are also arranged within the switch box and extended in an opposite direction with relation to the contacts 21.

Again referring to Fig. 1 of the drawings, wherein I have diagrammatically illustrated the electric circuit, 23 designates the trolley wire or other electrically charged element which supplies the conductor 24 with current for the operation of the car. A wire 25 is connected to this conductor, said wire extending to the motorman's signal lamp 11 in one end of the car and then from the lamp to one of the spring contact plates 22. A suitable resistance indicated at 26 is interposed in this circuit wire. A wire 27 is connected to the other of the spring contact plates 22 and to the corresponding plate in the switch box of the adjacent car door, a similar wire connecting the other of said plates in the latter switch box to one of the plates 22 of the switch arranged in the opposite end of the car. From the opposed plate 22 of this latter switch box, a wire 28 extends to the corresponding plate of the switch in the other end of the car and on the opposite side thereof. The plates 22 of the remaining switches on this side of the car are connected by wires as above described, and a wire 29 connects the signal lamp in the motorman's compartment at the opposite end of the car to that above referred to, with the plate 22 of the switch for the end door, as will be readily understood. From this latter lamp, a wire 30 ex-

tends to the ground indicated at 31. In this grounded wire, a switch 32 is located. From this description, it will be apparent that when all of the car doors 6 are closed, the switch plugs 15 being forced inwardly, the metal rings 20 are engaged with the opposed contact plates 22 and the lamps 11 being connected in series are illuminated when the circuit is thus closed. In the event, however, that any one of the several doors is not entirely closed, the circuit will be interrupted so that the lamps will not be illuminated. The motorman or conductor may readily ascertain which of the doors may have been inadvertently left open or is only partially closed owing to some derangement of the operating mechanism therefor, by viewing the several lamps 13 arranged above said doors. The lamp above the open door will be illuminated, said lamps being connected in multiple in the following manner: The circuit wire 33 in which a resistance 34 is located is joined to the wire 25 which in turn is connected to the conductor 24. This wire 33 is connected to one of the contacts 21 of the door switch at one end of the car. A wire 35 connects this wire 33 with the corresponding contact 21 of the switch at the opposite end of the car and on the same side, while a wire 36 is joined to this wire 35 and connected to the corresponding contact 21 of the central door switch. The other contact plates 21 of the door switches at opposite ends of the car are connected by a wire 37, which connects the end lamps 13. A wire 38 is connected to the other contact 21 of the central door switch and extends to the lamp 13 above said door and is joined to the wire 37. The contact plates 21 of the switches on the opposite side of the car are similarly connected to the several door lamps, the wires on this side of the car which connect the corresponding contacts being joined by means of the wires 39 and 40 to the corresponding wires 35 and 37 on the opposite side of the car. By means of this arrangement, it will be obvious that when all of the doors are tightly closed, the conducting rings 20 being out of engagement with the contact plates 21, the circuit through the lamps 13 will be broken. If for any reason, however, one of the doors is not closed, said ring engaging the spaced contacts 21 in the particular switch box 7 will close the circuit through the lamp arranged above that door, and illuminate the same, thus disclosing to the conductor or motorman which one of the several doors is open. As above explained, while the door remains in its open position, the motorman's lamp is not illuminated.

When several of the cars are coupled together to form a train, the circuits for the motorman's signal lamps in the several cars are connected by a plug and socket prefer-

ably constructed in the manner shown in Figs. 3 to 5 inclusive of the drawings. In the end wall of one car a casing of porcelain or other insulating material indicated at 41 is arranged, said casing being preferably of conical form and having an attaching plate 42 secured upon its larger end. This casing is centrally bored as at 43 to receive the metal socket member 44 which is provided with an annular flange 45 on one end to extend into an annular enlargement 46 of the bore 43. This flange is preferably formed with screw receiving openings whereby the socket member may be rigidly secured to the insulating casing. The socket member 44 is split at opposite points to provide longitudinally extending spring tongues 47, the free ends of which are normally disposed inwardly of the periphery of said member, and formed upon their inner faces with lugs or projections 48. To the closed end of the socket member, a wire 49 is electrically connected while the other end of said wire is joined to the circuit wire 30. An insulating block 50 is provided in which one end of the plug 51 is threaded. This plug tapers slightly and is adapted to be received in the socket member 44, said plug as it enters the open end of the socket member engaging the spring arms 47 thereof and forcing the same outwardly. At the inner or larger end of the tapered portion of the socket member, an annular groove 52 is formed in its periphery to receive the lugs or extensions 48 upon said spring arms, whereby the plug and socket member are held in proper electrical connection with each other. It is of course understood that a wire 53 is connected to the plug 51 and leads to one of the spring contacts 22 of the door switch at the end of the car. In this manner, it will be apparent that by simply opening all of the switches 32 with the exception of the one located upon the rear end car, the motorman's signal lamps upon all cars of the train are connected in series with a common operating circuit. This switch 32 on the last car, is of course closed in order to properly close the circuit through the ground.

From the foregoing description taken in connection with the accompanying drawings, it is believed that the construction, manner of operation and several advantages of my improved signaling system for street railways will be clearly and fully understood.

By the use of the invention, street railway accidents may be to a large extent obviated and considerable monetary loss to the company growing out of damage suits thus eliminated. Also, the conductor is relieved of considerable care and responsibility which is now required in the operation of cars provided with the ordinary signal bell. The

door lamps 13 afford a danger signal for the passengers as well as a means for locating any one of the several door operating mechanisms which may be out of order. My invention as a whole is also very simple in its construction and arrangement and may be manufactured and installed at comparatively small cost and without necessitating structural alterations in the cars.

The invention of course resides primarily in the manner of application of the apparatus to the car and the arrangement of the signal lamps in the circuit, and it will therefore be understood that while I have shown and described the particular construction of the door switch and plug and socket connection, I do not desire to be limited to the particular arrangement of the several parts comprised in these obviously necessary instrumentalities, but expressly reserve the privilege of adopting various other types of switches and circuit connectors which I may later find to be either more economical or better adapted to the particular exigencies arising from the application of the invention.

Having thus described the invention, what is claimed is:

1. The combination with a railway car provided with a plurality of entrance and exit doors, of motorman's signal lamps arranged in opposite ends of the car, a circuit for said lamps, switches arranged in the door jambs and connected in series in the circuit, said switches being operated by the doors when the same are closed to close said circuit, and an indicative signal adjacent to each door and operative when the door is open.

2. The combination with a street railway car provided with a plurality of entrance and exit doors, of motorman's signal lamps arranged in opposite ends of the car, a circuit for said lamps, an indicative device adjacent each of the doors, switches arranged in series in the circuit operated by the respective doors, whereby the circuit is closed and the signal lamps illuminated when all of the doors are closed, and a shunt circuit in which the indicative devices are connected in multiple, said switches being included in the shunt circuit whereby, when any one of the doors is opened, the indicative device adjacent thereto is operated.

3. The combination with a street railway car provided with a plurality of entrance and exit doors, of motorman's signal lamps arranged in the opposite ends of said car, a circuit therefor, switches arranged in the door jambs and connected in series in said circuit and operated when the doors are closed to close the circuit and illuminate the lamps, an indicative lamp adjacent to each of the doors, and a shunt circuit therefor which is closed by the respective switches

when any one of the doors is open, whereby the lamp adjacent to said door is illuminated.

4. The combination with a street railway car provided with a plurality of entrance and exit doors, of an indicative lamp adjacent to each of said doors, an electric circuit for said lamps, switches arranged in the jambs of the respective doors through which the lamps are connected in multiple in the circuit, whereby when any one of the several doors is open, the lamp adjacent thereto is illuminated.

5. The combination with a railway car provided with a plurality of entrance and exit doors, of motorman's signal lamps arranged in the opposite ends of said car, a circuit for said lamps, a switch arranged in the jamb of each door and each including spaced pairs of contacts, one pair of contacts of each switch being included in said

circuit, an indicative lamp adjacent to each of the doors, a shunt circuit for said lamps, said lamps being wired to the other pair of contacts of each switch, each of said switches also including a spring held circuit closing member engaged with the latter pair of contacts when the door with which the switch is associated is open, whereby the door lamps are individually illuminated, said circuit closing member being actuated by the door when the same is closed to engage the same with the first named pair of contacts, whereby the circuit is closed through the motorman's lamps when all of the doors are closed.

In testimony whereof I hereunto affix my signature in the presence of two witnesses.

EDWARD MORRIS.
